FOREIGN PATENT DOCUMENTS

GB	2246162	1/1992
JP	02164986	6/1990

Primary Examiner—Prabhakar Deshmukh*Assistant Examiner*—Derrick Holland(74) *Attorney, Agent, or Firm*—Calfee, Halter & Griswold LLP(57) **CLAIM**

I claim the ornamental design for a lock, as shown and described.

DESCRIPTION

FIG. 1 is a front perspective view of a lock showing my new design;

FIG. 2 is a top plan view thereof;

FIG. 3 is a front elevation view thereof;

FIG. 4 is a rear elevation view thereof;

FIG. 5 is a bottom plan view thereof;

FIG. 6 is a right side view thereof; and,

FIG. 7 is a left side view thereof.

The broken lines, which define the bounds of the claimed design, form no part thereof.

The broken lines shown represent unclaimed subject matter and form no part of the claimed design.
